CLAIM

The ornamental design for a baby stroller frame, as shown and described.

DESCRIPTION

FIG. 1 is a perspective view showing a first embodiment of baby stroller frame;

FIG. 2 is a right side view of a baby stroller frame FIG. 1, the left side being a mirror image thereof;

FIG. 3 is a front view of the baby stroller frame of FIG. 1; FIG. 4 is a top view of the baby stroller frame of FIG. 1; FIG. 5 is a bottom view of the baby stroller frame of FIG. 1; and,

FIG. 6 is a rear view of the baby stroller frame of FIG. 1.

The broken lines shown appearing in FIGS. 1-6 are for the purpose of illustration only, and form no part of the claimed design.
